INVENTOR

UNITED STATES PATENT OFFICE.

SAMUEL OAKMAN, OF BOSTON, MASSACHUSETTS.

IMPROVEMENT IN FORMERS FOR SEGMENTALLY SCREW-THREADED INSULATORS.

Specification forming part of Letters Patent No. **132,214**, dated October 15, 1872.

CASE A.

To all whom it may concern:

Be it known that I, SAMUEL OAKMAN, of Boston, in the county of Suffolk and State of Massachusetts, have invented a certain new and useful Mold for Telegraphic Insulators, of which the following is a specification:

The Nature of the Invention.

The nature of my invention consists in constructing a "point" for forming a segment-screw inside of a telegraphic insulator, said point consisting of a hollow tube the lower end of which is slotted. Within this tube a segment-screw is placed, said screw turning on its axis, so that in molding the insulator the screw-segment is at the slots in the outer tube; but when the molding is complete the screw-segments may be turned back within the tube and present a smooth space at the opening, thus allowing the point to be withdrawn.

Description of the Drawing.

Figure 1 is an elevation, showing the screw parts of the center-piece opposite the slots in the outer tube, as indicated also in Fig. 3. Fig. 2 is an elevation, as above, showing the smooth parts of the inner part opposite the slots in the outer tube, as indicated also in Fig. 4.

General Description.

Let A represent the outer part of the point.

This is made as shown in the drawing, and is provided with four openings or slots, C C C C. Within this tube the segment-screw bolt H is placed. This screw-bolt fits a corresponding screw within the tube A. The slots C C C C are cut through the tube A, as shown, and corresponding recesses E E E E, Fig. 4, planed into the center part H, so that if the screw-bolt H is turned, as shown in Figs. 1 and 3, the insulator molded upon the device will have within it segment-screws.

To withdraw this device from the insulator I have only to turn the bolt H to the position shown in Figs. 2 and 4. This action will present smooth surfaces to the inwardly-projecting screw-threads of the insulator and admit of the withdrawal of the device or "point."

K is a guide-pin inserted in the screw-bolt H, and projecting through the tube, as shown, so as to serve as a stop to limit the motion of the center-piece.

I claim as my invention—

The combination of the tube A with the center segment-screws H B B B B, substantially as described, and for the purpose set forth.

SAMUEL OAKMAN.
